UNITED STATES PATENT OFFICE.

WILLIAM NAFFIN, OF CAMDEN, NEW JERSEY.

COIN-CONTROLLED LOCK FOR DOORS.

1,175,795.

Specification of Letters Patent. Patented Mar. 14, 1916.

Application filed December 19, 1913, Serial No. 807,716. Renewed July 27, 1915. Serial No. 42,236.

To all whom it may concern:

Be it known that I, WILLIAM NAFFIN, a subject of the Emperor of Germany, residing at Camden, in the county of Camden 5 and State of New Jersey, have invented new and useful Improvements in Coin-Controlled Locks for Doors, of which the following is a specification.

This invention relates to coin-controlled 10 lock for doors, and is particularly designed to provide a lock for the doors of sanitary toilet closets, baggage and other lockers, etc.

The primary object of the invention is to provide a door lock mechanism which is 15 normally in locked position, against surreptitious opening from the outside, but which upon the deposit of a prescribed coin may be manipulated to unlock the door and allow it to be opened.

20 A further object of the invention is to provide a simple, reliable and efficient construction of coin-controlled lock which provides for the use of the coin as a power transmitting medium coupling elements of 25 the lock mechanism, and which is adapted to free the coin for deposit when the parts of the lock mechanism are returned to normal position.

25 A further object of the invention is to 30 provide a lock which may be released from the inside, and which allows of the lock bolt being directly unlocked by means of a master key without operating the coin-controlled elements of the lock mechanism.

35 A still further object of the invention is to provide a lock mechanism including a controlling key normally locked from movement and automatically released for movement by the actuation of the controlling 40 mechanism upon the deposit of a proper coin, which key may, if desired, be removed so that the door may be subsequently unlocked by the person depositing the coin.

45 A still further object of the invention is to provide a lock mechanism including a coin receptacle which may be locked in any preferred manner, and also additionally locked by the coin-controlled mechanism, thus giving added security.

50 The invention consists of the features of construction, combination and arrangement of parts herein fully described and claimed, reference being had to the accompanying drawings in which:—

55 Figure 1 is a view of a door embodying my invention, the door appearing in open-

position. Fig. 2 is a fragmentary rear elevation, showing the bolt releasing means upon the inside of the door and the lock mechanism applied thereto. Fig. 3 is a vertical transverse section through the rear portion of the lock casing, showing the parts of the controlling mechanism in rear elevation. Fig. 4 is a vertical front to rear section through the door and lock mechanism, 60 showing the parts in normal position. Fig. 5 is a view similar to Fig. 4 showing the parts of the controlling mechanism elevated to release the lock bolt for action. Fig. 6 is a horizontal transverse section on the line 6—6 of Fig. 5. Fig. 7 is a view similar to Fig. 3 showing the parts in the position illustrated in Fig. 5. Fig. 8 is a vertical transverse section taken substantially on the line 8—8 of Fig. 4, showing the parts in 65 the position shown in Figs. 5 and 7. Fig. 9 is a detail view of the actuating plunger. Fig. 10 is a similar view of one of the guides thereof. Fig. 11 is a fragmentary perspective view of the coin chute. Fig. 12 is a view 70 of one of the key grippers. Fig. 13 is a similar view of the key. Fig. 14 is a detail view of the shank portion of the key and the collar thereon.

Referring to the drawings, 1 designates 85 the door of a closet, locker or other like compartment, which is provided with slots 2 and 3 extending therethrough, and to the outer face of which is secured a guard or escutcheon plate 4 having a slot 5 registering with the slot 2 and slots 6 and 7 registering with the slot 3, the slot 7 constituting a coin induction slot.

Secured to the rear face of the door is a lock casing 8 including a front plate 9, a 95 supporting or partition plate 10 disposed between said front plate and the back plate of the casing, and a horizontal partition plate 11. The partition 11 provides a lower compartment for containing a coin receptacle 12, which may be in the form of a drawer normally locked against removal by a bolt 13, adapted to be actuated by any suitable type of key, not herein shown, said bolt being adapted to engage a keeper socket 100 in the plate 11, by which the drawer or receptacle is secured against intrusion except by an authorized person possessing a proper type of key.

Mounted in the lock casing is a transversely sliding bolt 14 adapted to engage 110 a suitable keeper on the door frame to lock

the door in closed position. To the relatively inner end of this bolt, which passes completely through the casing, is attached one end of a chain or other flexible releasing connection 15 carrying an actuating handle 16, the other end of said chain or connection passing around a suitably journaled drum 17. It will be evident, of course, that by drawing inwardly on the chain the bolt 5 may be retracted to unlock the door by a person from the inside of the closet, locker or other apartment. The shaft 18 of the drum 17 may be exposed through a key hole 19 in the door and suitably formed for engagement with a master key, whereby the bolt may be retracted and the door unlocked by an authorized person without actuating the coin governed lock controlling mechanism.

20 The bolt 14 is recessed to receive the bit 20 of a key 21, adapted to be inserted and withdrawn through the slots 2 and 5, said key having an angular shank 22 extending beyond its bit portion. The key when inserted is adapted to be engaged and normally locked against rotation and removal by a pair of grippers 23 slidable in suitable guides 24 and angularly recessed to engage the angular stem of the key, one of said 25 grippers being provided with projections 25 to interlock with a recess 26 in the key stem, and whereby the key will be held from rotation and also from longitudinal movement and withdrawal.

30 The grippers 23 are connected by toggle links 27 with a vertical sliding rod 28 adapted to be engaged at its lower end by a gravity retracted releasing rod or bar 29 connected with or otherwise receiving motion from a sliding primary operating device 30 having a portion projecting downward through and movable within the slot 6 and connected with a vertically movable operating knob or handle 31. The parts of 35 the mechanism for locking and releasing the key are inclosed within the space or chamber formed between the front wall 9 and partition plate 10 of the lock casing, as clearly indicated in Fig. 4.

35 The plate 11 is provided with a slot 32 with which normally communicates the lower end of a coin chute or conductor 33 carried by the sliding operating member 30, which chute normally communicates at its 40 inner and outer end with the coin induction slot 7. The lower end of the chute is partially open for the outward projection of a coin 34 introduced therein, and is formed with a seat or abutment 35 against which 45 the edge of the coin is adapted to bear until discharged through the slot 32 into the receptacle 12. The plate 10 is provided with guide slots 36 and 37, in the former of which the lower end of the chute 33 is vertically 50 movable.

The coin 34 when introduced into the slot 7 drops by gravity to the lower end of the chute in register with the slot 32 and is normally held from dropping downward into said slot by a pivoted gravity-controlled weight or detent 38, which partially guards the slot 32 and the opening in the end of the chute and presses the coin against the seat or abutment 35. The said detent 38 is pivoted at its upper end by a pin 39 to 55 ears 40 formed on a pair of spaced guide members 41 secured to the rear side of the wall 10, and is adapted for outward pivotal movement toward the rear wall of the casing to release the coin 34 under certain conditions. A releasing plunger 42 is movable between the guide members 41 and is provided at its sides with guide flanges or ribs 43 engaging guide grooves 44 in said guide members. At the lower end the plunger is 60 segmentally cut away to form a guide recess 45 to receive the edge of the coin disposed in the lower end of the chute, so that when a proper coin is deposited such coin will form a connection between the chute and the plunger 42 allowing the latter to be forced upward for a lock releasing action. When no coin is present in the lower end of the chute, any upward movement of the operating member 30 would be of no effect 65 in actuating the plunger 42, since the lower end of the chute is bifurcated or slotted, as at 46 to receive the web 47 left remaining at the lower end of the plunger by the formation of the recess 45, so that the operating 70 member and chute may move upward to a normal degree under such conditions without imparting motion to the slide. If desired the chute may be provided with a locking pin 48 to engage a keener 49 on the coin receptacle 12, to give additional security against the surreptitious opening or withdrawal of said receptacle by an unauthorized person. The releasing plunger 42 is disposed beneath a stop 50 formed on the 75 operating member 30 and movable in the slot 37, which stop is normally engaged and held from any but a restricted upward movement by a horizontal sliding detent 51 mounted on a guide plate 52 and normally held in the path of said stop by a spring 53. The plunger 42 is connected with the detent by a releasing link 54 and has projecting upwardly therefrom a stem 55 movable vertically through a guide opening in the stop 50 and carrying at its upper end a cam shoe or head 56. The shoe 56 on being moved upward is adapted to engage the cam member 57 of a pivoted, curved locking finger 58 engaging a recess 59 in a flange or collar 60 120 detachably fixed to the shank 22, whereby the key is normally held from rotation and can not be operated, even in the event of inoperativeness of the grippers 23. The collar 60 may be secured to the shank 22 by a 125

pin 60^a upon the removal of which said collar may be detached from the key.

In the use of my invention upon the door of a sanitary closet, it will of course be understood that upon the deposit of a proper coin in the chute 33 the coin will be held between the abutment 35 and detent 38 and prevented from dropping down through the slot 32. The person depositing the coin may accordingly move the handle 31 upward, thus transmitting similar motion to the operating member 30 and chute 33 and also to the plunger 42 through the connection between the operating member and chute formed by the coin 34. On such upward movement of the parts, the coin is held in position by the detent 38 and the detent or sliding stop 51 is moved against the resistance of the spring 53 out of the path of the stop 50, allowing the parts mentioned to be moved to the limit of their upward movements. Motion is accordingly transmitted to the member 29 and thence to the rod 28 and through the links 27 to the grippers 23, thus retracting the latter to permit the key to be drawn outward or turned. At the same time the cam shoe 56 is projected upward and engages the cam 57 thus tilting the finger 58 out of engagement with the recess 59 and releasing the shank 22 so that the key may be turned to enable the bolt 14 to be retracted. The door may thereupon be opened and then locked in closed position and the bolt finally retracted through the releasing connection 15 to enable the person to pass out. When the door is opened and subsequently closed, upon the release of the handle 31 the parts of the controlling mechanism drop by gravity to normal position and the detent 38 swings backward under the momentum of the closing movement of the door, allowing the coin 34 to drop through the slot into the receptacle 32.

It will be understood, of course, that in the use of the device upon a sanitary toilet door, the key may be fixed against withdrawal and released for rotary motion only under the action of the coin-controlled mechanism, as it is desirable to allow the door to be opened once only for the deposit of each coin of the proper denomination.

In the practical use of the device upon a toilet door proper instructions will be applied to the door stating that after inserting the proper coin, the operator should raise the knob, turn the key in the proper direction to unlock the door and then pull the door open. When the lock is used on the door of a baggage locker or similar compartment, proper directions will be placed upon the door to indicate that the operator should first insert a proper coin in the slot, then raise the knob and turn the key in the proper direction to unlock the door, and

pull the door open and take out the key before releasing hold of the knob. Also that when the party returns to remove the stored article, a coin should be inserted, the knob raised, the key inserted and turned to unlock the door, and the door opened, the grippers 23 thereupon locking the key from removal. The parts 57 and 60 are dispensed with when the lock is used on a baggage locker or like compartment, as these elements will ordinarily prevent the key from being removed.

I claim:

1. In a lock, a bolt, a key for actuating the same, an operating member normally held from movement, a coin chute movable with said member, releasing means adapted to be connected by a coin with the chute to free said operating member for actuation, means for normally locking the key from rotation, and means operable through the movement of the operating member when released for freeing the key for rotation.

2. In a lock, a bolt, a key for actuating the same, a locking device for normally holding the key from rotation, an operating device, a coin chute connected therewith, a releasing plunger adapted to be coupled by the coin to the operating device, a detent for normally holding the plunger from movement, and means carried by the plunger for successively rendering the detent and locking means inoperative to permit motion of the operating device and free the key for rotation.

3. In a lock, a bolt, a key for actuating the same, a device for locking the key from rotation, a device for locking the key from movement and withdrawal, an operating device, means operable upon the movement thereof to retract the key locking devices, a detent for holding the operating device from movement, a coin chute connected with the operating device, a plunger adapted to be coupled by the inserted coin with the chute, and means controlled by the plunger for successively retracting the detent and releasing the key locking devices.

4. In a lock, a bolt, a key for actuating the same, an operating device, a locking device for holding the key from rotation, a coin chute connected with the operating device, a detent for holding the operating device from movement, a plunger coupled to the operating device by the inserted coin, means operated thereby for successively retracting the detent and key locking device, and a gravity controlled coin detent adapted to maintain the coin in engagement with the chute until the key is released and to be retracted by the motion of the door when closed and locked to free the coin for final deposit.

5. In a door lock, a locking bolt, a key for operating the same, a locking device for holding the key from rotation, an operating

member, a detent for holding the same from movement, a plunger adapted to be coupled to the operating member by the inserted coin, means controlled by the slide for reTRACTING the detent and first-named locking device, and means controlled by the operating member for retracting the second-named locking device.

6. In a lock for doors, a locking bolt, a key for actuating the same, a locking device to engage and hold the key from rotation, a locking device for holding the key from withdrawal, a sliding operating device, means directly controlled thereby for

releasing the second-named locking device, 15 a detent for holding the sliding operating device from movement, and a sliding plunger adapted to be coupled to the sliding operating device by the inserted coin for successively retracting the detent and releasing 20 the first-named locking device.

In testimony whereof I affix my signature in presence of two witnesses.

WILLIAM NAFFIN.
